[57] CLAIM

The ornamental design for a cryotherapeutic device, as shown and described herein.

DESCRIPTION

FIG. 1 is a perspective view of a cryotherapeutic device showing my new design;

FIG. 2 is a frontal elevation thereof;

FIG. 3 is a side elevation thereof both sides being generally the same except that one is the mirror image of the other;

FIG. 4 is a rear elevation thereof;

FIG. 5 is a top view thereof; and,

FIG. 6 is a bottom view thereof.
